ARTHUR C. SOULE, OF SAN FRANCISCO, CALIFORNIA.

SASH MOUNTING.

Application filed January 30, 1928. Serial No. 250,418.

This invention relates particularly to a mounting for supporting and controlling the opening and closing movements of an individual sash or a plurality of sashes or other 5 analogous inclosures.

An object of the invention is to provide a mounting for sashes that will be superior in point of simplicity, inexpensiveness of construction, positiveness of operation and facility and convenience in use and general efficiency.

A further object of the invention is to provide a mounting or mountings for supporting a sash or a plurality of sashes or other analogous inclosures, within an enclosing frame, for controlling and regulating the opening and closing movements of the sash or sashes and having means thereon to regulate the friction of the moving parts of the sash 20 mountings.

A still further object of the invention is to provide in combination with a window frame and plurality of sashes, of means interposed between the sashes and frame to maintain the 25 sashes in any desired opened or closed position against wind pressure and the like.

Other objects and advantages will appear as this description progresses.

In this specification and the annexed drawings, the invention is illustrated in the form considered to be the best, but it is to be understood that the invention is not limited to such form, because it may be embodied in other forms, and it is also to be understood 35 that in and by the claims following the description, it is desired to cover the invention in whatsoever form it may be embodied.

In the accompanying one sheet of drawings:

40 Fig. 1 represents a vertical section through a window frame having a plurality of sashes mounted therein on a mounting constructed in accordance with my invention.

Fig. 2 is an enlarged vertical cross section 45 taken through a side of a window frame and a single sash in the closed position, having my sash operating mechanism mounted thereon.

Fig. 3 is a fragmentary detail of a manually 50 operable stop bar for engaging the head rail of one of the sashes to hold it in a selected open position.

Fig. 4 is an enlarged front elevation of a fragmentary part of the adjuster for the sash supporting arm.

Fig. 5 is a vertical section taken through Fig. 4 on the line 5—5.

Fig. 6 is a front elevation of one of the sash slide shoes.

Fig. 7 is a side elevation of Fig. 6.

Fig. 8 represents a vertical section through a window frame having a plurality of sashes supported thereon, on a modified form of mounting constructed in accordance with my invention.

Fig. 9 is a fragmentary plan view of one of the sashes shown in Fig. 8, taken on the line 9—9 of Fig. 8.

Fig. 10 is an enlarged front elevation of the device for joining the sash supporting arms to the window frame.

Fig. 11 is a cross section taken through Fig. 10, on the line 11—11.

Fig. 12 is a fragmentary vertical section of the window frame through the lower sash, showing the method of supporting the lower 75 sash in the window frame.

This invention relates to the pivoting of a plurality of window sashes, on the opposite stiles of each sash, at a pair of corresponding points, to slide shoes which are slidably retained in independent guides on opposite sides of the casement or window frame and connecting all of the sashes together by common support arms, connected at corresponding points on opposite sides to each of the sashes, 80 each of said support arms being adjustably pivoted to the window frame.

In detail, the construction illustrated in the drawings includes a window frame composed of a sill 1, stool 2, and side jambs 3 connected 90 across the top by the lintel 4, together with the usual stops 5 or other weather proofing finish mounted on the interior of the jambs, stool and lintel.

Each of the jambs 3 of the frame are either 95 channeled to form guideways 7 or are provided with guideways thereon which said guideways are arranged in a relatively vertical position and in alignment with each other on the opposite side jambs. The stops 5 are 100 secured to the jambs 3 to partially cover the guideway 7 so as to finish the interior of the window frame in accordance with standard practice.

A plurality of pairs of slide shoes 12, consisting of metal members with flange ends 11, are slidably retained in each of the guideways. A plurality of separate sashes 8, 9

and 10 are arranged in the window frame to cover the entire area thereof and each sash is supported on its opposite stiles, at a pair of corresponding points, to slide shoes which 5 are slidably mounted in the opposite guideways. The sash 8 at corresponding points on its opposite side stiles and adjacent an end thereof, is pivotally connected by the pivots 13 on the sash plate 19, to the slide shoes 12 10 in the opposite guideways. Similarly, each of the sashes 9 and 10 at corresponding points on their opposite side stiles, and adjacent an end thereof, are pivotally connected by the pivots 13 on the sash plates 19 to slide shoes 15 12 on the opposite guideways. The slide shoes 12 support each of the sashes 8, 9 and 10 for sliding movement in a vertical direction and also permit the sashes, individually or in unison, to be swung outwardly from a 20 closed vertical position to a substantially reversed position.

Each of the sashes are operatively supported in the window frame in either the closed vertical position, or in an open position 25 or in a reversed position, by support arms 24. All of the sashes are supported by common support arms, there being a support arm connected to one side of all of the sashes and a similar support arm connected to an opposite side of the sashes. Each of the sash support arms 24 are pivoted at 25 to a plate 26 on the opposite stiles of the sash 8, at a point between the horizontal center of said sash and the free end thereof. The same support 30 arms are pivoted at 27 to a plate 28 on the opposite stiles of the sash 9 at substantially the horizontal center thereof, and said arms are pivoted at 29 to a plate 30 secured to the sash 10 between the horizontal center thereof 35 and head rail thereof, whereby the opposite support arms 24 are connected to all of the sashes.

The lower end of each control arm 24 is pivoted at 31 to a bearing plate 32 arranged 45 at the lower end of the guideway 7. Each bearing plate 32 is secured by screws 33 to the opposite sides of the window frame. The plate 32 is provided with an arcuate slot 34 therein, cut on a radius struck from the pivotal 50 axis of the pivot 31, and a fastening screw 35 is arranged in each arm 24, to pass through the slot 34 in each bearing plate 32.

A yieldable or resilient friction plate 36 has an end thereof secured to the under side arm 55 of the pivot 31. The friction plate 36 is co-extensive with the arm 24, and the free end of the friction plate 36 is tapped to be engaged by the threaded end of an adjusting screw 35. By tightening on the screw 35, the control 60 arm 24 and the friction plate 36 are drawn tightly against the opposite faces of the bearing plate 32 and frictionally engaged therewith. As the adjusting screw 35 is loosened the friction plate 36 tends to draw away from 65 the under side of the bearing plate 32 to di-

minish the frictional resistance between the arm 24, friction plate 36 and the bearing plate. The adjusting screw 35 functions as a regulatory medium by means of which the friction on the control arm 24 may be increased or diminished so as to control movement of the sash mounting. The screw 35 controls the entire operation of the sash mounting, making it possible to hold the sashes in any desired position without fear 70 that wind pressure or the like will cause the position of any sash or plurality of sashes to be changed. A sash or plurality of sashes supported upon my sash mounting does not require any auxiliary or additional mechanism to hold any single sash or plurality of sashes in a closed or opened or partly opened or reversed position. The manner in which the support arms are secured to all of the sashes permits of all said sashes to be opened 75 or closed simultaneously and in unison. 80

The sashes illustrated in the drawings, when operatively installed in a window frame, are opened best by manually pushing outward upon the lower rail of any one of 90 the sashes. As the lower end of the sash is moved, the support arms 24 are swung outwardly, causing the sashes, not pushed, to open outwardly, in accordance with the movement imparted to the manually moved 95 sash. Movement of the free end of one sash causes the opposite ends of all the sashes on the slide shoes to slide in the guideways and the supporting arms to swing relative to the frame. The construction of the sash mounting is such that all of the sashes mounted thereon may be substantially reversed in the window frame simultaneously or independently, so as to present the outer surface of one or more of the sashes to the interior of a room to facilitate washing. 100 105

In order to hold the sashes in a selected open position, I have pivoted a stop arm 40 on a pivot 41, mounted upon a plate 42 that is secured to one of the side jambs. The plate 40 is pivoted at one end so that the opposite end of the said plate is free to follow any opening movement of the sash to which it is related. A stop pin 43 is mounted on the plate 42, to limit the downward pivotal movement of the stop 40, while a pin 44 limits the pivotal movement of said plate in an opposite direction. When the sashes are swung into the open position as shown in Fig. 1, a stop arm 40 will swing down automatically 110 into the position shown in Figs. 1 and 3, the free end of the plate 40 engaging the face of the sash, and stopping the downward sliding movement of the head rail of the sash. By reason of all of the sashes being connected to a common supporting arm, whereby all of the sashes operate in unison, the said stop plane 40 causes all of the sashes to be stopped 115 in a selected open position. 120 125

In the modified form of the invention 130

shown in Figs. 8 to 12 inclusive, I provide the window frame comprised of the sill 50, stile 51, and side jambs 53 connected across the top by a lintel 54, together with the usual 5 finishing material 55. Each of the jambs 53 are provided with guideways 57 therein, the same as in the preferred form of the invention heretofore described. A plurality of pairs of slide shoes 62, consisting of metal 10 members having flanged ends 61, are slidably retained in each of the guideways 57. A plurality of separate sashes 58, 59 and 60 are arranged in the window frame to cover the opening therein, and each sash is supported 15 on its opposite stiles, at a pair of corresponding points, to a pair of slide shoes which are slidably mounted in the opposite guideways. The sash 58, at corresponding points on its opposite side stiles and adjacent an end 20 thereof, is pivotally connected by the pivots 63 on the sash plate 69 to the slide shoes 62 in each of the opposite guideways. Similarly, each of the sashes 59 and 60 at corresponding points on their opposite side stiles, and adja- 25 cent an end thereof, are pivotally connected by pivots 63 on the sash plates 69 to slide shoes 62 on the opposite guideways. The slide shoes 62 support each of the sashes 58, 59 and 60 in the window frame.

30 The sashes 58 and 59 are supported by common support arms 74, there being a separate arm connected to one side of each of the sashes 58 and 59, and a similar support arm connected to the opposite side of said sashes. 35 Each of the sash support arms 74 are pivoted at 75 to a plate 76 on the opposite stiles of the sash 58 at a point between the horizontal center of said sash and the free end thereof. The same support arms are pivoted at 57 to a plate 57' on the opposite stiles of the sash 59 at substantially the horizontal center thereof. The lower end of each control arm 54 is pivoted at 81 to a bearing plate 82 arranged at the lower end of the guideway 57, each 40 bearing plate 82 being secured at opposite sides of the window frame. Each plate 82 is provided with an arcuate slot 84 therein, cut on a radius struck from the pivotal axis of the pivot 81, and a fastening screw 85 is ar- 45 ranged in each arm 74 to pass through the slot 84 in each bearing plate 81. A friction plate 86, below the plate 82, is secured at one end to the under side of the pivot 81 and the free end of the plate 86 is tapped to be 50 engaged by the threaded end of an adjusting screw 85. The adjusting screw 85 functions to move the plate 86 relative to the plate 82 and as a regulatory medium by means of the friction created thereby, the control arm 74 55 may be regulated as desired to control movement of the sash mounting.

A link 45 is pivotally mounted on the pivot 63 that connects the slide shoe 62 to the sash 59, there being one of the links 45 60 arranged on each of the opposite sides of the sash at corresponding positions thereon. The opposite ends of each of the links 45 are pivotally connected at 46 to the opposite side stiles of the sash 58. The links 45 are pivoted to the respective sashes 58 and 59 65 to lie exactly parallel to the control arms 74 that support the said sashes 58 and 59. The links 45 are offset so that when the sashes 58 and 59 are arranged in the vertical closed position, said links will not interfere with 70 the supporting arms 74 moving into the closed position. Likewise, the links 45 lie relatively close to the stiles of each of the sashes 58 and 59, whereas the control arms 74 are secured to the sashes 58 and 59 on 75 U-shaped brackets 76 and 57' respectively, which project a slight distance out from the edge of the sash stiles. The links 45 and the support arms 74 swing in different planes to avoid any interference between them in 80 operation, and the mediate portion of the links 45 is offset relative to its opposite ends to avoid any possible conflict with the control arms 74. The links 45 keep the sashes 85 58 and 59 in a predetermined spaced relation 90 at all times, and cooperate with the arms 74 whereby the sashes 58 and 59 may be moved in absolute unison into any selected open or closed position.

The modified form of the invention differs 95 from the preferred form in that the lower sash 60 is not pivotally connected to the control arms 24, but said lower sash is carried by its own individual supporting arms. Each side of the lower sash 60 is provided 100 with a support arm 47 pivoted at 79, to a plate 80 secured to the side of said sash 60 between the horizontal center thereof and the head rail thereof. The lower end of the support arm 47 is secured to the pivot 81 105 on the bearing plate 82, which, said pivot 81 also supports the control bars 74 that supports the sashes 58 and 59. The adjusting screw 85 heretofore described, also functions as the regulatory medium by means 110 of which the friction on the control arm 47 may be increased or diminished so as to control movement of the mounting of the lower sash 60, and its supporting mechanism. 115

Each of the supporting arms 47 are arranged between each supporting bar 74 and the side stile of the sash, whereby the lower sash 60 may be opened and closed independently of the upper sashes 58 and 59, or the 120 upper sashes 58 and 59 may be opened and closed independently of the lower sash 60. However, in order that all of the sashes 58, 59 and 60, may move in unison if desired, I have provided a spring arm 90, that is 125 secured at 91, to the inside face of each of the control arms 47. The opposite end of the spring arm 90 is provided with a U-shaped socket 92 therein, that is adapted to extend completely around the control arm 130

47, from the under side thereof, and to project beyond the outside face thereof into the path of travel of the sash supporting arms 74. Each socket 92 will thus spring into engagement with its corresponding control arm 74, whereby the control arms 74 and 47 may be made to move in unison. The socket 92 will connect the control arms 74 and 47 together, whereby all of the sashes 58, 59 and 60 may be opened, and then, if desired, the sockets 92 may be disengaged from the support arms 74, whereby the lower sash 60 may be closed, or the upper sashes 58 and 59 may be closed, or vice versa. As it often happens in ventilating rooms and buildings, conditions may be such that selective ventilation in either the lower or upper part of the room is required, and my mechanism herein described, provides a multiple sash supporting mechanism in which one or more sashes of a group may be disconnected from the group of sashes and operating mechanism therefor, and opened or closed while in the disconnected position. The socket 92 that is used to connect the support arms 47 and 74 together, is operated manually in effecting disengagement of the arms, whereas to engage the support arms 74 with the sockets 92, I have provided a rounded edge 93 on one side of each socket 92 which will permit of an automatic entry of the arm 74 into the socket 92.

Although I have shown and described a particular method of and apparatus for mounting a plurality of sashes within the window frame, whereby one or more sashes of the group may be disassociated therefrom and operated independently thereof, it is to be understood that I do not limit myself to the particular form of the mechanism shown.

Although I have shown and described a mounting for a plurality of sashes with particular reference to wooden sashes, it is to be understood that it would be clearly within the scope of the invention to utilize such a sash mounting on different kinds of windows and transoms, and also that the sash mountings can be applied to a casement window operating in a horizontal plane, as well as a vertically positioned sash adapted to operate in a vertical plane.

Having thus described this invention, what I claim and desire to secure by Letters Patent is:

1. A window construction comprising a frame; guides on opposite sides thereof; plural pairs of slide shoes engaging the opposed guides; a plurality of sashes in said frame, each pivotally connected at corresponding points on opposite sides to a pair of slide shoes; and means pivotally connected at corresponding points to each of the opposite sides of all of said sashes and pivotally connected to opposite sides of the frame to move all of the sashes simultaneously and to

maintain the planes of said sashes in uniform spaced relation in the opened and closed positions.

2. A window construction comprised of a frame; guides on opposite sides thereof; a plurality of separate sashes in said frame each having an end thereof slidably related to the opposed guides in the frame; and, means pivotally connected at corresponding points to each of the opposite sides of all of said sashes and pivotally connected to opposite sides of the frame to move all of the sashes simultaneously and to maintain the planes of said sashes in uniform spaced relation in the opened and closed positions. 80

3. A window construction comprising a frame; guides on opposite sides thereof; plural pairs of slide shoes engaging the opposed guides; a plurality of sashes in said frame each pivotally connected at corresponding points on opposite sides to a pair of slide shoes; and an arm pivotally connected at corresponding points to opposite sides of each of said sashes and pivotally connected to opposite sides of the frame for supporting said sashes in any selected opened and closed position. 85

4. A window construction comprised of a frame; guides on opposite sides thereof; a plurality of separate sashes in said frame each having an end thereof slidably related to the opposed guides in the frame; and an arm pivotally connected at corresponding points to opposite sides of each of said sashes and pivotally connected to opposite sides of the frame to permit said sashes to be simultaneously opened and reversed in said frame. 95

5. A window construction comprised of a frame; guides on opposite sides thereof; a plurality of separate sashes in said frame, each sash having slide shoes pivotally connected to corresponding points on opposite sides of an end thereof and slidably related to the opposite guides in the frame; and, means pivotally connected at corresponding points to each of the opposite sides of all of said sashes and pivotally connected to opposite sides of the frame to move all of the sashes simultaneously and to maintain the planes of said sashes in uniform spaced relation in the opened and closed positions. 105

6. A window construction comprised of a frame; guides on opposite sides thereof; a plurality of separate sashes in said frame, each sash having slide shoes pivotally connected to corresponding points on opposite sides of an end thereof and slidably related to the opposite guides in the frame; and an arm pivotally connected at corresponding points to opposite sides of each of said sashes and pivotally connected to opposite sides of the frame to permit said sashes to be simultaneously opened and reversed in said frame. 120

7. A window construction comprising a frame; guides on opposite sides thereof; plu- 130

- ral pairs of slide shoes engaging the opposed guides; a plurality of sashes in said frame each pivotally connected at corresponding points on opposite sides to a pair of slide 5 shoes; an arm pivotally connected at corresponding points to opposite sides of each of said sashes and pivotally connected to opposite sides of the frame to permit said sashes to be opened and reversed in said frame; and 10 means to create friction between each arm and a related part of the sash supporting mechanism to resist movement of the sashes from any selected position.
8. A window construction comprised of a frame; guides on opposite sides thereof; a plurality of separate sashes in said frame each having an end thereof slidably related to the opposed guides in the frame; an arm pivotally connected at corresponding points 15 to opposite sides of each of said sashes and pivotally connected to opposite sides of the frame to permit said sashes to be opened and reversed in said frame; and means to create friction between each arm and a related part 20 of the sash supporting mechanism to resist movement of the sashes from any selected position.
9. A window construction comprised of a frame; guides on opposite sides thereof; a plurality of separate sashes in said frame, each sash having slide shoes pivotally connected to opposite sides of an end thereof and slidably related to the opposite guides in the frame; an arm pivotally connected at corresponding 25 points to opposite sides of each of said sashes and pivotally connected to opposite sides of the frame to permit all of said sashes to be simultaneously placed in any selected opened and closed position; a friction plate on each of the opposite sides of the frame related to the pivot holding an end of each arm to the frame; and adjustable means to regulate the contacting relationship between each arm and friction plate to control the ease with which the sashes may be simultaneously opened and closed.
10. A window construction comprising a frame; guides on opposite sides thereof; plural pairs of slide shoes engaging the opposed guides; a plurality of sashes in said frame each pivotally connected at corresponding points on opposite sides to a pair of slide shoes; an arm pivotally connected at corresponding points to opposite sides of each of said sashes and pivotally connected to opposite sides of the frame to permit all of said sashes to be simultaneously placed in any selected opened and closed position; a friction plate on each of the opposite sides of the frame related to the pivot holding an end of each arm to the frame; and adjustable means to regulate the contacting relationship between each arm and friction plate to control the ease with which the sashes may be simultaneously opened and closed.
11. A window construction comprised of a frame; guides on opposite sides thereof; a plurality of separate sashes in said frame each having an end thereof slidably related to the 55 frame to permit all of said sashes to be simultaneously placed in any selected opened and closed position; a friction plate on each of the opposite sides of the frame related to the pivot holding an end of each arm to the frame; and adjustable means to regulate the contacting relationship between each arm and friction plate to control the ease with which the sashes may be simultaneously opened and closed.
12. A window construction comprised of a frame; guides on opposite sides thereof; a plurality of separate sashes in said frame, each sash having slide shoes pivotally connected to corresponding points on opposite sides of an end thereof and slidably related to the opposite guides in the frame; an arm pivotally connected at corresponding points to opposite sides of each of said sashes and pivotally connected to opposite sides of the frame to permit all of said sashes to be simultaneously placed in any selected opened and closed position; a friction plate on each of the opposite sides of the frame related to the pivot holding an end of each arm to the frame; and adjustable means to regulate the contacting relationship between each arm and friction plate to control the ease with which the sashes may be simultaneously opened and closed.
13. A window construction comprising a frame; guides on opposite sides thereof; plural pairs of slide shoes engaging the opposed guides; a plurality of sashes in said frame each pivotally connected at corresponding points on opposite sides to a pair of slide shoes; an arm pivotally connected at corresponding points to opposite sides of each of said sashes and pivotally connected to opposite sides of the frame to permit all of said sashes to be simultaneously placed in any selected opened and closed position; a friction plate on each of the opposite sides of the frame related to the pivot holding an end of each arm to the frame; and adjustable means to regulate the contacting relationship between each arm and friction plate to control the ease with which the sashes may be simultaneously opened and closed.
14. A window construction comprised of a frame; guides on opposite sides thereof; a plurality of separate sashes in said frame each having an end thereof slidably related to the opposed guides in the frame; an arm pivotally connected at corresponding points to opposite sides of each of said sashes and pivotally connected to opposite sides of the frame to permit all of said sashes to be si-

multaneously placed in any selected opened and closed position; a friction plate on each of the opposite sides of the frame related to the pivot holding an end of each arm to the 5 frame and having an arcuate slot therein; a bar secured to each arm pivot on the under-side of each wear plate; and an adjusting screw in each arm passed through the slot in each friction plate into threaded engagement 10 with the bar to regulate the contacting relationship between each arm and bar and friction plate to control the freeness with which the sashes may be simultaneously opened and closed.

15. 15. A window construction comprised of a frame; guides on opposite sides thereof; a plurality of separate sashes in said frame, each sash having slide shoes pivotally connected to corresponding points on opposite 20 sides of an end thereof and slidably related to the opposite guides in the frame; an arm pivotally connected at corresponding points to opposite sides of each of said sashes and pivotally connected to opposite sides of the 25 frame to permit all of said sashes to be simultaneously placed in any selected opened and closed position; a friction plate on each of the opposite sides of the frame related to the pivot holding an end of each arm to the 30 frame and having an arcuate slot therein; a bar secured to each arm pivot on the under-side of each wear plate; and an adjusting screw in each arm passed through the slot in each friction plate into threaded engagement 35 with the bar to regulate the contacting relationship between each arm and bar and friction plate to control the freeness with which the sashes may be simultaneously opened and closed.

40. 16. A window construction comprising a frame; guides on opposite sides thereof; plural pairs of slide shoes engaging the opposed guides; a plurality of sashes in said frame each pivotally connected at corresponding points on opposite sides to a pair of slide shoes; means pivotally connected at corresponding points to each of the opposite sides of each of said sashes and pivotally connected to opposite sides of the frame to move 45 all of the sashes simultaneously and to maintain the planes of sashes in uniform spaced relation in the opened and closed position; and means on the frame to stop all of the sashes in a selected open position.

50. 17. A window construction comprised of a frame; guides on opposite sides thereof; a plurality of separate sashes in said frame each having an end thereof slidably related to the opposed guides in the frame; means 55 pivotally connected at corresponding points to each of the opposite sides of all of said sashes and pivotally connected to opposite sides of the frame to move all of the sashes simultaneously and to maintain the planes of said sashes in uniform spaced relation in the

opened and closed positions, and means on the frame to stop all of the sashes in a selected open position.

18. A window construction comprised of a frame; guides on opposite sides thereof; a plurality of separate sashes in said frame, each sash having slide shoes pivotally connected to corresponding points on opposite sides of an end thereof and slidably related to the opposite guides in the frame; an arm pivotally connected at corresponding points to opposite sides of each of said sashes and pivotally connected to opposite sides of the frame to permit said sashes to be simultaneously opened and reversed in said frame; and means on the frame to stop all of the sashes in a selected open position.

19. A window construction comprised of a frame; guides on opposite sides of said frame; a pair of separate sashes in said frame, each sash having slide shoes pivotally connected to corresponding points on opposite sides of an end thereof and slidably related to the opposite guides in the frame; an arm pivotally connected at corresponding points on the opposite sides of a pair of said sashes and pivotally connected to opposite sides of the frame to permit said sashes to be simultaneously opened and reversed in said frame; a single sash in the frame having slide shoes pivotally connected to corresponding points on opposite sides of an end thereof and slidably related to the opposite guides in the frame; an arm pivotally connected at corresponding points on the opposite sides of said single sash and pivotally connected to opposite sides of the frame to permit said single sash to be opened and reversed in said frame; and means to detachably connect the arms on the single sash with the arms on the pair of sashes to move all of the sashes in unison or to move the pair of sashes independently of the single sash, and vice versa.

20. A window construction comprised of a frame; guides on opposite sides of said frame; a pair of separate sashes in said frame, each sash having slide shoes pivotally connected to corresponding points on opposite sides of an end thereof and slidably related to the opposite guides in the frame; an arm pivotally connected at corresponding points on the opposite sides of a pair of said sashes and pivotally connected to opposite sides of the frame to permit said sashes to be simultaneously opened and reversed in said frame; a single sash in the frame having slide shoes pivotally connected to corresponding points on opposite sides of an end thereof and slidably related to the opposite guides in the frame; an arm pivotally connected at corresponding points on the opposite sides of said single sash and pivotally connected to opposite sides of the frame to permit said single sash to be opened and reversed in said frame; means to create friction between each

- arm and a related part of the sash supporting mechanism to resist movement of the sashes from any selected position; and means to detachably connect the arms on the single sash 5 with the arms on the pair of sashes to move all of the sashes in unison or to move the pair of sashes independently of the single sash, and vice versa.
21. A window construction comprised of a frame; guides on opposite sides of said frame; a pair of separate sashes in said frame, each sash having slide shoes pivotally connected to corresponding points on opposite sides of an end thereof and slidably related to the opposite guides in the frame; an arm pivotally connected at corresponding points on the opposite sides of a pair of said sashes and pivotally connected to opposite sides of the frame to permit said sashes to be simultaneously opened and reversed in said frame; a single sash in the frame having slide shoes pivotally connected to corresponding points on opposite sides of an end thereof and slidably related to the opposite sides of said 25 single sash and pivotally connected to opposite sides of the frame to permit said single sash to be opened and reversed in said frame; a friction plate on each of the opposite sides of the frame related to the pivot holding an end of each of the arms to the frame; adjustable means to regulate the contacting relationship between the arm ends and friction plate to control the ease with which the sashes may be simultaneously opened and closed; 30 and means to detachably connect the arms on the single sash with the arms on the pair of sashes to move all of the sashes in unison or to move the pair of sashes independently of the single sash, and vice versa.
22. A window construction comprised of a frame; guides on opposite sides thereof; a plurality of separate sashes in said frame, each sash having slide shoes pivotally connected to opposite sides of an end thereof and slidably related to the opposite guides in the frame; an arm pivotally connected at corresponding points to opposite sides of each of said sashes and pivotally connected to opposite sides of the frame to permit said sashes 45 to be opened and reversed in said frame; a link pivotally connected to the ends of a pair of the sashes, adjacent the sliding ends thereof and parallelly to the sash support arms, to maintain the pair of sashes in a predetermined spaced relation in all closed and opened positions; and means to create friction between each arm and a related part of the sash supporting mechanism to resist movement of the sashes from any selected position.
23. A window construction comprising a frame; guides on opposite sides thereof; plural pairs of slide shoes engaging the opposed guides; a plurality of sashes in said frame each pivotally connected at corresponding points on opposite sides to a pair 55 of slide shoes; an arm pivotally connected at corresponding points to opposite sides of each of said sashes and pivotally connected to opposite sides of the frame to permit all of said sashes to be simultaneously placed in any selected opened and closed position; a link pivotally connected to the ends of a pair of the sashes, adjacent the sliding ends thereof and parallelly to the sash support arms, to maintain the pair of sashes in a predetermined spaced relation in all closed and opened positions; and means on the frame to engage a face of one of the sash to stop all of the sashes in a selected open position.
24. A window construction comprised of a frame; guides on opposite sides thereof; a plurality of separate sashes in said frame each having an end thereof slidably related to the opposed guides in the frame; a friction plate on each of the opposite sides of the frame related to the pivot holding an end of each arm to the frame; and adjustable means to regulate the contacting relationship between each arm and friction plate to control the ease with which the sashes may be simultaneously opened and closed.
25. A window construction comprising a frame; guides on opposite sides thereof; plural pairs of slide shoes engaging the opposed guides; a plurality of sashes in said frame each pivotally connected at corresponding points on opposite sides to a pair of slide shoes; means pivotally connected at corresponding points to opposite sides of each of said sashes and pivotally connected to opposite sides of the frame for supporting said sashes in any selected opened and closed position; a link pivotally connected to the ends of a pair of the sashes, adjacent the sliding ends thereof and parallelly to the sash support arms, to maintain the pair of sashes in a predetermined spaced relation in all closed and opened positions; and means on the frame to engage a face of one of the sash to stop all of the sashes in a selected open position.
26. A window construction comprised of a frame; guides on opposite sides thereof; a plurality of separate sashes in said frame each having an end thereof slidably related to the opposed guides in the frame; means pivotally connected at corresponding points

to opposite sides of each of said sashes and pivotally connected to opposite sides of the frame to permit said sashes to be simultaneously opened and reversed in said frame; 5 a link pivotally connected to the ends of a pair of the sashes, adjacent the sliding ends thereof and parallelly to the sash support arms, to maintain the pair of sashes in a pre-determined spaced relation in all closed and 10 opened positions; and means on the frame to engage a face of one of the sash to stop all of the sashes in a selected open position.

27. A window construction comprised of a frame; guides on opposite sides thereof; a 15 plurality of separate sashes in said frame, each sash having slide shoes pivotally connected to corresponding points on opposite sides of an end thereof and slidably related

to the opposite guides in the frame; an arm pivotally connected at corresponding points 20 to opposite sides of each of said sashes and pivotally connected to opposite sides of the frame to permit said sashes to be simultaneously opened and reversed in said frame; a link pivotally connected to the ends of a 25 pair of the sashes, adjacent the sliding ends thereof and parallelly to the sash support arms, to maintain the pair of sashes in a pre-determined spaced relation in all closed and opened positions; and means on the frame to 30 engage a face of one of the sash to stop all of the sashes in a selected open position.

In testimony whereof, I have hereunto set my hand at San Francisco, California, this 30th day of December, 1927.

ARTHUR C. SOULE.
